UNITED STATES PATENT OFFICE.

MARVIN L. HAMMITT, OF CARBONITE, IDAHO, ASSIGNOR OF ONE-HALF TO AXEL B. LARSON, OF CARBONITE, IDAHO.

COLLAR-BUTTON.

1,335,164.

Specification of Letters Patent. Patented Mar. 30, 1920.

Application filed March 10, 1919. Serial No. 281,796.

To all whom it may concern:

Be it known that I, MARVIN L. HAMMITT, a citizen of the United States, residing at Carbonite, in the county of Shoshone and 5 State of Idaho, have invented certain new and useful Improvements in Collar-Buttons, of which the following is a specification.

The present invention relates to an improved collar button for use at the back of 10 the neck of the wearer, to provide for a proper position of the collar, especially those of the fold type, and to form a fastening device that may be applied with facility, and which when once applied lies flat against 15 the neck band and collar, providing for facile manipulation of the neck tie or scarf, and eliminating pressure at the back of the neck.

The invention consists in a one piece fastener of metal or celluloid, fashioned with 20 particular and novel lines to furnish the desired form and outline of such a device for accomplishing its functions.

In the accompanying drawings one complete example of the physical embodiment 25 of the invention is illustrated, constructed and arranged according to the best mode so far devised for the practical application of the principles of the invention.

Figure 1 is a view in front elevation of 30 the fastener or button.

Fig. 2 is an edge view of the device.

Fig. 3 is a top edge view of the device.

Fig. 4 is a sectional view through a collar and neck band of a shirt, showing the 35 application thereto of the device of the invention.

In the preferred form of the invention as 40 illustrated in the drawings, the device is made of metal, celluloid, or other suitable material that possesses a degree of resiliency, and the body 1 illustrated as of triangular form or heart-shape is preferably cut out at 1^a to lighten the weight of the device, as

well as to add to the resiliency of the material, the point P of the body being adapted to pass through the button hole in the neck band, and the horizontal shoulders H, H, at the top of the body presenting a straight edge within the laundried neck band 50 B to prevent upward movement of the device after once being positioned.

Above the body portion a neck 2 is fashioned, the material being offset to the rear, and of sufficient width to receive the outer 55 portion of the neck band B and the inner ply of the collar C which is "buttoned" thereon in Fig. 4. Preferably the bend is rounded as at 2^a so that the round bend will touch the collar, or rather the outer ply 60 thereof and in the space above this bend and the top of the fold collar, the necktie may be retained.

The head 3 has side wings as 3' 3' forming 65 an elongated member disposed horizontally with rounded ends and curved to conform to the collar C when in use. The entire device is "dished" or curved to conform to the rounded collar and neck band, and the collar is "buttoned" over the head by slipping 70 the button hole of the collar over one of the wings as the initial movement, and then the entire head is passed through the button hole and the collar adjusted with the head above the button hole and the collar securely 75 fastened to the neck band of the shirt S.

What I claim is:—

A collar fastening device comprising a 80 triangular shaped body portion with a lower point and upper horizontal square edge, a neck projected above and centrally of the body and fashioned with an offset formed 85 with a rounded bend to support a tie, a head above the neck also offset from the body and having lateral wings, and said device curved to conform to the collar and shirt band.

In testimony whereof I affix my signature.

MARVIN L. HAMMITT.
